UNITED STATES PATENT OFFICE

EZRA FORD, OF TARRANT, ALABAMA

SPIKE PULLER

Application filed February 18, 1929. Serial No. 340,905.

This invention appertains to devices for extracting large nails, spikes and the like and more particularly to a spike puller for railroad tracks.

One of the primary objects of the invention is to provide a novel railroad spike puller embodying a body block for engaging the rail and an operating lever carrying claws for engaging a spike on either side of the rail, whereby the spikes can be conveniently and easily operated from each side of the rail without undue exertion on the part of the operator.

A further object of the invention is the provision of novel clamping members associated with the body block for engaging the rail to hold the block in proper position on the rail against movement during actuation of the operating lever.

A further object of the invention is the provision of locking members for clamps, so as to insure the proper holding of the clamps in engagement with the rail.

A further object of the invention is the provision of means carried by the opposite ends of the body block whereby the same can be readily grasped to facilitate the sliding of the block along the rail to different positions thereon.

A still further object of the invention is the provision of a railroad spike extractor of the above character, which will be durable and efficient in use, one that will be simple and easy to manufacture, and one which can be placed upon the market at a reasonable cost.

With these and other objects in view, the invention consists in the novel construction, arrangement and formation of parts, as will be hereinafter more specifically described, claimed, and illustrated in the accompanying drawings, in which drawings:—

Figure 1 is a side elevation of the improved spike extractor showing the same in operative clamped position on a rail;

Figure 2 is a top plan view of the spike extractor showing the same applied to a rail;

Figure 3 is a transverse section taken on the line 3—3 of Figure 2 looking in the direction of the arrows illustrating one of the claws 50 engaging a spike preparatory to extracting or pulling the same from the tie.

Figure 4 is a transverse section through the device taken on the line 4—4 of Figure 1 looking in the direction of the arrows illustrating the novel clamp carried by the body block for engaging the rail; 55

Figure 5 is a longitudinal section through the improved device taken on the line 5—5 of Figure 2 looking in the direction of the arrows; 60

Figure 6 is an enlarged detail sectional view taken on the line 6—6 of Figure 3 looking in the direction of the arrows showing the claw engaging a spike, and 65

Figure 7 is a detail perspective view of one of the spike engaging claws.

Referring to the drawings in detail, wherein similar reference characters designate corresponding parts throughout the several views, the letter A generally indicates my improved spike puller and B a railroad track of any conventional construction. 70

The railroad track B includes the usual railroad ties 10 and rail 11. As shown, the rail includes the ball or head 12, the web 13, and the base flanges 14. The spikes 15 are employed for holding the rails on the ties. 75

The improved spike puller A comprises a base block 20 which can have its outer face curved transversely if preferred. The lower face of the base block 20 is provided with a longitudinally extending groove 21 for snugly receiving the head or ball 12 of a rail and the flanges 22 defined by said groove engage the opposite sides of the ball of the rail and prevent lateral shifting of the block. 80

The block is provided on its upper face adjacent each end thereof with transversely extending grooves 23 and intermediate its ends 85

and between the grooves 23 with a central transverse groove 24. The block is provided with a longitudinally extending central bore 25 which receives a removable longitudinally extending pivot 26 which, as shown, terminates short of the end transverse groove 23. This pin 26 has rockably mounted thereon the operating lever 27 of the spike puller and the groove 24 is so arranged that the lever can be 10 swung from one side of the block to the other and the lever on each side and above its pivot carries spike extracting claws 28 and 29. These claws are rockably carried by the lever and so arranged that one claw can be used 15 for one side of the rail for extracting spikes while the other claw can be used on the other side of the rail for extracting spikes. The lever 27, as shown, is provided with a relatively short handle, but it is to be understood 20 that an extension hand grip can be associated therewith if desired.

In order to hold the base block on the rail against longitudinal movement and in order to further brace the same against lateral 25 shifting during the extracting of a spike, novel clamps 30 and 31 are carried by the opposite ends of the block. Each clamp includes jaws 32 and 33 which depend from the opposite sides of the base block 21 and 30 these jaws have formed on their upper end inwardly extending pivot ears 34. The base block itself on the opposite side of the longitudinal bore 25 is provided with side bores 35 which extend through or communicate 35 with the end transverse grooves 23 and the ears 34 are placed in said grooves after which the pivot pins 36 are slid in the bores 35. This effectively holds the jaws in position for swinging movement. The lower ends of the 40 jaws are provided with inwardly directed hooks 37 for engaging the base flanges 14 of the rails and the jaws above the hooks are provided with blocks 38 for clamping engagement with the web of the rail. A contractile coil spring connects the two jaws together on each side of the pivot point thereof and normally tends to swing the jaws in open 45 position out of clamping engagement with the rail.

50 When it is desired to clamp the base block in position swinging latches 40, carried by the base block are moved into engagement with the jaws and these latches effectively hold the jaws in clamping position. Each of the swinging latches 40 carry a manipulating handle 41.

In operation of my improved device, when 55 it is desired to extract the spikes from the tie the base block is placed on the rail in the desired position and held in place by the clamps after which the lever 27 is swung to one side and the claw is inserted over the head of the spike. The lever is now moved upwardly and the spike will be conveniently and expeditiously pulled from the tie.

In a device of this kind, spikes can be conveniently removed from the ties on high trestles and the like in that spikes can be removed from both sides of the rail from the center of the trestles.

The spike puller can be conveniently moved along the rail from place to place by grasping the pivoted bail handles 42 carried by each end of the block for this purpose.

Changes in details may be made without departing from the spirit or the scope of this invention, but:—

What I claim as new is:

1. A railroad spike puller comprising a base block, means carried by the opposite ends of the base block for clamping engagement with a rail, an operating lever rockably carried by the base block for movement on opposite sides thereof, and depending spike engaging claws rockably secured to the lever above the pivot point thereof.

2. A railroad spike puller comprising an elongated base block having a groove in its lower face for receiving the ball of a rail, clamps carried by the opposite ends of the base block each including pivoted jaws having means for engaging the base flanges of a rail, means carried by the block for holding the jaws in gripping contact with the rail, a swinging operating lever carried by the base block, intermediate the clamps for swinging movement of each side of the base block, and pivoted claws carried by the lever above and on the same side of the pivot point thereof.

3. A railroad spike remover comprising a longitudinally extending base block having a groove in its lower face for receiving the ball of a rail, the base block being provided with end transverse grooves and an intermediate transverse groove, the base block being also provided with a longitudinally extending central bore opening into the intermediate transverse groove and side longitudinally extending bores opening into the end transverse groove, pivot pins mounted in said bores, a lever rockably mounted on the pivot pin mounted in the central longitudinal bore and arranged in the intermediate transverse groove, claws rockably carried by the lever above and on the same side of the pivot point of the lever, clamps for each end of the block for engaging the rail each including jaws having inwardly directed pivot ears extending into the end transverse grooves, pivot pins extending through the pivot ears and into the side longitudinally extending bores, and swinging latches for engaging the jaws for holding the same in clamping contact with the rail.

4. A railroad spike extractor comprising an elongated body having a longitudinally extending groove in its lower face for receiving the ball of a rail, a swinging lever carried by the base block, spike engaging claws rockably secured to the lever above and

on the same side of the pivot point of said lever, a clamp carried by the base block including jaws arranged on each side of the base block and pivotally connected thereto,
5 swinging latches carried by the base block for movement over the jaws for moving and holding the same in contact with the rail, each jaw including a lower hooked end for engaging the base flange of a rail and an inwardly
10 directed jaw base for engaging the web of the rail.

In testimony whereof I affix my signature.
EZRA FORD.
